UNITED STATES PATENT OFFICE.

ERASTUS WOODWARD, OF SOMERVILLE, MASSACHUSETTS.

SEWING-MACHINE.

SPECIFICATION forming part of Letters Patent No. 426,159, dated April 22, 1890.

Application filed May 18, 1889. Serial No. 311,308. (No model.)

To all whom it may concern:

Be it known that I, ERASTUS WOODWARD, of Somerville, in the county of Middlesex and State of Massachusetts, have invented certain new and useful Improvements in Sewing-Machines, of which the following, taken in connection with the accompanying drawings, is a specification.

The object of my invention is to combine in a sewing-machine devices by which the length of stitch may be automatically changed in alternation—that is, a long stitch may follow a short one, or vice versa; also, to combine with a sewing-machine a device by which alternating stitches of different lengths may be varied in their relative lengths to any desired extent, or all of the stitches may be of the same length, as in the ordinary machines. This object I attain by the mechanism shown in the accompanying drawings, in which—

Figure 1 is a side elevation of my machine, a part of the casing being represented as broken out, so as to show the moving parts more clearly. Fig. 2 is a longitudinal vertical section of the same. Fig. 3 is a front elevation of the same, a part of the face-plate being broken out. Fig. 4 is a vertical cross-section taken on line xx of Fig. 2. Fig. 5 is a plan showing a part of the feed device; Fig. 6, cross vertical sectional view showing parts of the feed device and presser-foot. Fig. 7 is a detailed view showing parts of the needle-bar, presser-foot, and shuttle. Fig. 8 is a horizontal section of the cam-plates and their adjuncts, the same being shown in side elevation, Fig. 1. Fig. 9 is an elevation of one of the feed-cams—that is, the rear one of Figs. 1 and 2—and some of the parts which are operated by it. Fig. 10 is an elevation of one of the cams—that is, the middle cam of Figs. 1 and 2—and some of the parts which are operated by it. Fig. 11 is an elevation showing the presser-foot rod and upper feed-clamp rod and connected devices. Fig. 12 is a sectional plan showing most of the parts shown in elevation in Fig. 11. Fig. 13 is a detail in horizontal section. Fig. 14 is a diagram showing a variety of stitching.

In Figs. 1 and 2, A A' A² represent the frame and casing of the machine, of which B is the main shaft and B', the driving-pulley. The needle B⁶ is affixed to the needle-bar B⁵, and is driven by means of the crank-disk B³

on the main shaft B, the crank-pin of which works in a cross-head B⁴, attached to the needle-bar B⁵.

The shuttle of this machine and its connected devices are very similar to those of other machines, and need not be particularly described. The shuttle-carrier C⁹, Figs. 1 and 2, is attached, as shown, to the shaft C⁸, which is made to make part rotations back and forth by means of the lever-arm C⁷, link C⁶, (see Fig. 4,) and lever C⁴, said lever C⁴ being pivoted at C⁵ to the frame of the machine, Figs. 1, 2, and 4. The upper arm C² of the lever C⁴ has upon it a pin, which works in a cam-groove made in the rear face of the gear-wheel C. As the cam-wheel C rotates but once while the main shaft B (driving the needle) rotates twice, it is necessary to so form its cam-groove that the shuttle shall perform its full motions twice at each one rotation of the cam-wheel C.

My fabric holding and feed device consists, first, of the ordinary presser-foot L and throat-plate T, Figs. 3 and 7, and, second, of two feeding-clamps F² F⁴ and K¹¹, Figs. 3 and 6. Of these the clamp F² F⁴ presses the fabric from the under side and the clamp K¹¹ from the upper side. Thus the two clamps F² F⁴ and K¹¹ grasp and hold the fabric between them and feed it along the required distance, but do not release it until the presser-foot L comes down onto it and, in connection with the throat-plate T, holds it. Then the clamps F² F⁴ and K¹¹ loosen their grasp and move back to a position for again grasping the fabric ready to move it for the next stitch. The lower feed-clamp consists of the sliding block F² and the pin F⁴, (see Figs. 5 and 6,) so that the fabric is clamped between the pin F⁴ and the upper feed-clamp K¹¹. By this device the fabric may be turned very readily when the presser-foot L is raised from it.

The object of having a single pin or stud F⁴ for the lower feed is that by having but one point of pressure between the upper and lower feed-clamps the fabric being operated upon may, while still clamped by the upper and lower feed-clamps, be turned so that the direction of the line of stitches can be abruptly changed without stopping the machine, this characteristic being of great advantage when the machine is used for basting.

I will now describe the mechanism for operating the two feed-clamps $F^2 F^4$ and K^{11} . The shaft C' is driven by the wheel C , Figs. 1, 2, 8, 9, and 10. On the shaft C' , I have two face-cams D and H . The cam D has a cam-groove D' , in which a pin on the end of the lever D^2 works, causing the said lever D^2 to swing on its pivot D^5 , Fig. 4. The fulcrum D^5 is affixed to a block D^4 , which slides in a groove D^8 , made in the lower end of the lever D^2 . Said fulcrum is also connected to a sliding bracket D^6 , said bracket D^6 being adapted to be moved up and down by the finger-pin D^7 . The lower end of the lever D^2 has attached to it a boss D^9 , Figs. 1 and 2, in which a pin D^{13} , Fig. 2, is made fast. Upon this pin D^{13} a link D^{10} is hung, the upper end of said link D^{10} being hung onto a short shaft or journal D^8 , attached to the frame of the machine by cross-bars $A^4 A^4$. It will be observed if the fulcrum D^5 , Fig. 4, be moved down (by the sliding bracket D^6) until it is opposite the pin D^{13} , Figs. 2, 9, and 10, then the lever D^2 will simply swing about the fulcrum D^5 and give no back-and-forth motion to the pin D^{13} , and hence the link D^{10} will remain stationary; but if the fulcrum D^5 is moved upward then the lower end of the lever D^2 oscillates to correspond with the oscillations of its upper end, caused by the cam D . The pin has a lever H^{14} hung upon it, (see Figs. 1, 9, and 10,) the upper end H^{13} of which is connected by a link H^{12} to a lever H^{10} , Fig. 9, hung on the journal D^8 , so that the lever H^{14} must partake of the movement of the lever H^{10} , as well as of the cam-lever D^2 ; but the lever H^{10} is controlled in its movements by the second cam-lever H^2 , which has a sliding fulcrum extending from the bracket H^6 , Fig. 1, said bracket H^6 being adjustable up and down by the finger-pin H^7 . The second cam-lever H^2 is operated by the cam H , and is in its construction and formation like the first cam-lever D^2 , although its movement is different, as it is operated by the cam-groove H' . (See dotted lines in Fig. 9.) As the two cam-levers D^2 and H^2 are both connected (indirectly) to the lever H^{14} and both have adjustable fulcrums, it is evident that the said lever H^{14} can be made to stand still when the other parts of the machine are in motion, (by so adjusting the fulcrums that their lower ends are simply swinging points,) and also that one of them may be made inoperative so far as the lever H^{14} is concerned and the other operative, or they may alternately cause the lever H^{14} to move, each giving it an equal motion, or they may be so set that one of them shall give the lever H^{14} a comparatively slight movement, while the other shall give it a greater movement.

The lever H^{14} controls the movement of the feeding-clamps $F^2 F^4$ and K^{11} , already referred to, by means of the following-described mechanisms:

H^{15} , Fig. 4, is a link connecting the lever H^{14} to the rocker-arm H^{16} on the shaft H^{17} .

F , Fig. 3, is an arm extending from the rocker-shaft H^{17} to a link F' , which connects it to the lower feeding-clamp $F^2 F^4$. 70

K , Fig. 4, is a slotted arm, also extending from the rocker-shaft H^{17} , to which it is attached by means of a clamping-screw K' , an adjusting-slot K^2 , and a link K^3 , which is attached at its upper end to an arm K^4 on the rocker-shaft K^5 , Figs. 3 and 4. The rocker-shaft K^5 has upon it an arm K^6 , Fig. 3, which is connected by a link K^7 to the sliding block K^8 . Affixed to the sliding block K^8 is the post K^{10} of the upper feed-clamp K^{11} . 80

The sliding block K^8 , Fig. 3, is guided in its motion by the rod k , affixed in the head-block K^9 . The head-block K^9 is attached to the vertical rod K^{12} , which is arranged to slide up and down. The spring K^{13} acts on the block K^{14} to keep the rod K^{12} down—that is, to cause the upper feed-clamp K^{11} to bear upon the work when it is desired to have it hold the work in place. 85

As both of the feeding-clamps $F^2 F^4$ and K^{11} are operated by the same rocker-shaft H^{17} , it is evident that the two must move simultaneously; but it is not necessary that the two shall have the same amount of motion, for by changing the working length of the arm F or of the arm K a different amount of motion may be given to its respective feeding-clamps. In the drawings, Fig. 4, I have shown one K of the arms provided with a slot K^2 , so that its working length may be varied for the purpose of giving more or less throw to the feeding-clamp K^{11} . The object of having an unequal movement to the feeding-clamps is to cause (when desired) one of the layers of fabric to be "gathered" at the same time that it is sewed or basted. 95

The presser-foot L , Figs. 3 and 7, is attached to a rod L^2 by a clamp L' . Said rod L^2 has a spring L^3 , which, acting on the block L^4 , attached to the presser-foot rod L^2 , tends to keep the presser-foot L down to its working position. 100

The presser-foot L and the upper feed-clamp K^{11} are caused to be lifted from the work by the following-described device, (see Figs. 11, 12, and 13.) 115

B^7 is a cam-block attached to the needle-bar B^5 and is provided with a cam-groove B^8 , which, as the needle-bar B^5 moves up and down, gives motion to the arm M on the rocker-shaft A^6 , which in turn gives motion to the forked arm M' , also attached to the rocker-shaft A^6 . The fork M^2 of the arm M' embraces a pin M^3 on an arm M^4 , which causes the rocker-shaft A^7 to make part rotations. 120

M^5 is a tumbler attached to the rocker-shaft A^7 and is made to oscillate with it. The arms of the tumbler M^5 engage with the under sides of the blocks L^4 and K^{14} , attached, respectively, to the presser-foot rod L^2 and the feed-clamp rod K^{12} , so that a movement of the tumbler M^5 as it oscillates will alternately lift and drop the presser-foot L and the feed-clamp K^{11} . (See also Figs. 3, 6, and 7.) 125

For convenience in lifting (manually) the presser-foot L and the feed-clamp K¹¹ when it is desired to place a fabric in the machine or to remove it, I have a cam N, Figs. 1, 2, and 5 3, which swings on a pivot-screw N' and may be turned by its handle N². This cam N is immediately under the projection-arm L⁷. (See Figs. 11 and 13.) The arm L⁷ extends into the block L⁴ L⁵, as shown in Fig. 13, and 10 is connected with a guiding-stem L⁶, which fits loosely in the head-block L⁴ L⁵, so that the head-block L⁴ L⁵, together with the presser-foot rod L², may be raised up without moving the arm L⁷ L⁸. That part of the arm 15 L⁷ L⁸ that is marked L⁸ extends back and under the projection K¹⁵ from the block K¹⁴, so that when the arm L⁷ L⁸ has been moved high enough it will come in contact with the projection K¹⁵, (see Figs. 11 and 13,) and 20 through it lift the upper feed-clamp K¹¹. The first movement of the cam N will cause the presser-foot L to rise up, but will not affect the upper feed-clamp K¹¹, for the reason that the part L⁸ of the arm L⁷ L⁸ is still below the 25 projection K¹⁵, as shown in Fig. 13.

I claim—

1. In a sewing-machine, the combination of the levers D² H², having fulcrums independently adjustable, and operating mechanism 30 connecting said levers to the lever H¹⁴, and lever H¹⁴, with mechanism adapted to transmit motion from said lever H¹⁴ to the upper and lower feeding-clamps, and said upper and lower feeding-clamps, the whole adapted to 35 give a long and short feed movement in alternation, substantially as and for the purpose set forth.

2. In a sewing-machine, an upper and lower feeding-clamp, the main shaft, the counter- 40 shaft having two feed-working cams, levers

D² H², operated by said cams, having adjustable fulcrums, a lever H¹³, connected to and operated by the said levers D² H², and mechanism for transmitting motion from said levers H¹³ to the said upper and lower feeding- 45 clamps, all adapted to vary the length of each alternate stitch, substantially as and for the purpose set forth.

3. In a sewing-machine, the combination of an upper feeding-clamp and a mechanism for giving said feeding-clamp a feed motion with a lower feeding-clamp and a mechanism for giving it a feeding motion, said upper and lower feeding mechanisms being independent 50 of each other and adapted to give to the upper and lower feeds motions variable in extent relatively to each other, and the cam-levers D² H², having adjustable fulcrums attached to the sliding brackets D⁶ H⁶, whereby feed motions are obtained variable in relation to 55 alternate stitches, as described, substantially as and for the purpose set forth.

4. In a sewing-machine, the combination of the needle-bar, cam-block B⁷, attached to the needle-bar and having the groove B⁸, arm M, 60 rocker-shaft A⁶, and arm M', and presser-foot rod L², having a presser-foot L and block L⁴, with the tumbler M⁵ and upper feed-clamp rod K¹², having a feed-clamp K¹¹ and lifting-block K¹⁴, substantially as and for the purpose set 65 forth.

In testimony whereof I have signed my name to this specification, in the presence of two subscribing witnesses, on this 14th day of May, A. D. 1889.

ERASTUS WOODWARD.

Witnesses:

FRANK G. PARKER,
MATTHEW M. BLUNT.
